UNITED STATES PATENT OFFICE

114,700

DESIGN FOR A DRESS ENSEMBLE

Charlotte Flusser, New York, N. Y.

Application February 20, 1939, Serial No. 83,097

Term of patent 3½ years

To all whom it may concern:

Be it known that I, Charlotte Flusser, a citizen of the United States, residing at New York city, in the county of New York and State of New York, have invented a new, original, and ornamental Design for a Dress Ensemble, of which the following is a specification, reference being had to the accompanying drawing, forming part thereof.

Fig. 1 is the front view of a dress ensemble showing my design;

Fig. 2 is a rear view of the ensemble as shown in Fig. 1;

Fig. 3 is a front view of the dress portion of the ensemble shown in Fig. 1;

Fig. 4 is a rear view of Fig. 3; and

Fig. 5 is an enlarged fragmentary view of the ensemble shown in Fig. 1 illustrating the elastic embroidery of the jacket and dress top.

I claim:

The ornamental design for a dress ensemble, substantially as shown and described.

CHARLOTTE FLUSSER.
